(57) **CLAIM**

The ornamental design for an X-flowpath muffler, as shown and described.

DESCRIPTION

FIG. 1 is a top, front, right side perspective view of the X-flowpath muffler present invention;

FIG. 2 is a front elevation view;

FIG. 3 is rear elevation view;

FIG. 4 is a right side elevation view, the left side elevation view being a mirror image;

FIG. 5 is a top plan view; and,

FIG. 6 is a bottom plan view.

The broken line showing in all drawings views is for the purpose of illustrating portions of the X-flow path muffler that forms no part of the claimed design.

1 Claim, 4 Drawing Sheets

FIG. 1

FIG. 2

FIG. 4

FIG. 3

FIG. 5

FIG. 6
